CLAIM

The ornamental design for a beekeeping cabinet, as shown and described.

DESCRIPTION

FIG. 1 is a perspective view of a beekeeping cabinet design according to our new design.

FIG. 2 is a perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view thereof, wherein a plurality of frames have been placed therein.

FIG. 10 is a perspective view showing alternate usage configurations of a FIG. 1.

FIG. 11 is a perspective view thereof;

FIG. 12 is a front elevational view thereof;

FIG. 13 is a rear elevational view thereof;

FIG. 14 is a left side elevational view thereof;

FIG. 15 is a right side elevational view thereof;

FIG. 16 is a top plan view thereof;

FIG. 17 is a bottom plan view thereof; and,

FIG. 18 is a perspective view thereof, wherein a plurality of frames have been placed therein.

The broken lines are shown for the purpose of illustrating parts of the beehive cabinet that form no part of the claimed design.
